UNITED STATES PATENT OFFICE.

FRANK W. MIX, OF NEW BRITAIN, CONNECTICUT.

DESIGN FOR A HASP-LOCK CASE.

SPECIFICATION forming part of Design No. 17,670, dated August 30, 1887.

Application filed July 13, 1887. Serial No. 241,225. Term of patent 7 years.

To all whom it may concern:

Be it known that I, FRANK W. MIX, a citizen of the United States, residing at New Britain, in the county of Hartford and State of Connecticut, have invented and produced a new and original Design for Trunk-Locks, of which the following is a specification, reference being had to the accompanying drawings, forming part thereof.

10 In the accompanying drawings, Figure 1 is a plan view of my newly-designed lock. Fig. 2 is a view of the locking-plate, and Fig. 3 is a view in section through the hasp and locking-plate.

15 The leading features of my design consist in a rib on the front face of the locking-plate, the said rib conforming in shape to the lower edge of the pendent hasp-plate, and a hasp-plate having a cap-plate on its front face and a smooth rear face.

20 A represents the hasp-plate, jointed at B, the lower end of said hasp-plate being slightly greater in width than the width of the body portion of said hasp-plate. The body or swing-25 ing portion of the hasp-plate A has a smooth rear face except at the point c, that rests immediately over the bolt-opening in the locking-plate, and with an outwardly bulging-cap, C, on the lower end of its front face. The locking-plate D is provided on its front face with

a rib conforming in shape to the contour of the lower end of the hasp-plate, and the cap on the lower end of the hasp-plate with a bolt hole or opening and with perforated ears d. The upper portion of the hasp-plate has gradually tapering irregular outline, the edges of which are offset, as is also the extreme upper end, b.

35 Having fully described my design, what I claim as new, and desire to secure by Letters Patent, is—

1. In a design for a hasp-lock case, the design for the locking-plate, consisting of the peripheral rib on the front face thereof and the opening in the space partly inclosed by the 45 rib, as shown and described.

2. In a design for a hasp-lock case, the design for the hasp-plate, consisting of the enlarged lower end and the outwardly-bulging cap on the front face of said lower end, as 50 shown and described.

3. The design for a hasp-lock case, the same consisting of the enlarged lower end of the hasp and the outwardly-projecting rib on the locking-plate, as shown and described.

FRANK W. MIX.
